UNITED STATES PATENT OFFICE.

GEORGE H. WILSON, OF AUGUSTA, GEORGIA.

ATTACHMENT FOR SLASHERS AND FINISHERS.

1,377,044.

Specification of Letters Patent.

Patented May 3, 1921.

Application filed May 7, 1919. Serial No. 295,430.

To all whom it may concern:

Be it known that GEORGE H. WILSON, citizen of the United States, residing at Augusta, in the county of Richmond and 5 State of Georgia, has invented new and useful Improvements in Attachments for Slashers and Finishers, of which the following is a specification.

The object of the invention is to provide 10 an attachment for the slasher and finisher commonly used in the textile art whereby the warp threads may be so operated upon that those lying in the selvage are offset at specified points, thus providing a gap in 15 the warp which will serve, in conjunction with a stopping device applied to the loom, to positively stop the latter. Warps run in the ordinary way will not accomplish this result. The improved device herein shown 20 and described works with the usual cut marker and each time a cut mark is made with die in the usual way, the improved device operates upon the selvage warp threads to offset them. The use of the device re- 25 lieves the operator of the trouble of watching for cut marks and in this way allows one operator to increase the number of looms which he or she may run and the operator can devote all his or her attention 30 to the general stopping caused by the warp threads breaking.

Another object of the invention is to provide means for the purpose specified which is simple in construction, durable and effective in operation and inexpensive to 35 manufacture and apply.

Other objects appear in the following description wherein the invention is set forth in detail. The invention is illustrated and 40 described in a specific embodiment, to which, however, it is not to be restricted. The right is reserved to make such changes or alterations as the actual reduction to practice may suggest insofar as such changes or 45 alterations are compatible in spirit with the annexed claims.

In the accompanying drawings:

Figure 1 is a view in side elevation of a slasher and finisher with the cut marking device attached thereto.

Fig. 2 is a top plan view of the structure in Fig. 1.

Fig. 3 is an enlarged side elevational view of that part of the device operating upon 55 the selvage warp threads to effect the offsetting referred to.

Fig. 4 is a view of the structure of Fig. 3 taken in the plane of the line 4—4.

Fig. 5 is a section on the line 5—5 of Fig. 3.

Fig. 6 is a diagrammatic view to illustrate the effect of the operation of the device on the selvage warp threads.

Fig. 7 is a section on the line 7—7 of Fig. 4.

Referring to the drawings, there is shown in Figs. 1 and 2 a slashing and finishing machine which comprises the usual sizing apparatus 1, the heated drum 2, the usual guide rolls 3, the leash-rods 4 and the removable beam 5. This apparatus just described follows the ordinary well-known construction, the warp being led from appropriate beams (not shown), thence to the size-box 1, thence over heated drum 2 and 70 around same to the uppermost of the guide rolls 3, so that it completely encircles the drum, thence around the other guide rolls and around the leash-rods to removable beam 5. The warp threads in this apparatus are of course separated between the leashing means and the beam by an appropriate comb but the latter forms no part of the present invention. The present invention resides in means for offsetting the 75 outermost warp threads on one edge, so that a gap of specified length will occur in the selvage on one side. For the purpose of providing means for automatically stopping the loom when this gap appears on the latter, the gap is formed where the usual cut 80 mark is made with an appropriate marking apparatus or die and the improved apparatus can be used with or without the die marking apparatus. The gap referred to 85 indicates that a point in the warp has been reached where a cut is to be made.

The guide rolls are of course put in motion in the usual way and that roller on the extreme left hand end of the apparatus has 90 attached to its shaft a worm wheel 6 meshing with a worm 7 carried by the shaft 8 to which power is transmitted by appropriate means (not shown). This shaft 8 is an essential part of the usual form of slasher and the improved device is operated partly by this shaft and partly by the shaft 9 which is also an essential part of the usual 95 form of slasher. Shaft 9 terminates adjacent the comb 10 and carries on its extremity a gear 11, this gear meshing with a gear 12 which is mounted on one extremity of a 100 105 110

shaft 13 journaled in appropriate bearing standards 14 carried by the frame of the slasher. The warp threads pass between the teeth of the comb 10 and over the roller 3^a which carries the worm gear 6 and the selvage warp threads are operated upon by the improved device between the comb and the roller 3^a, this device operating at specified intervals indicating that a certain number of yards of warp have passed this point.

The warp threads having been treated in the size-box and passed over the heating drum 2, if the outside threads be pressed in after such operation, the sizing will cause adjacent threads to stick together, thus leaving a gap, as indicated at 15 in Fig. 6, the latter being a diagrammatic view illustrating as a plain surface the let-out of the warp threads.

20 The outer selvage warp threads are compressed in at specified intervals by means of a roller 16 which is formed with a grooved periphery and disposed so that its axis is vertical. This roller is carried in a fork 18' and is rotatably mounted on a bolt 17 extending through the two legs of the fork. The fork is mounted at the extremity of an arm 19 which is slidably carried in the legs of a U-shaped member 20, the latter being carried by an appropriate bracket 21 by means of which it is separated on the frame of the machine.

25 The U-shaped member 20 is disposed in the direction of the width of the machine—that is, in the direction of the length of the guide rolls and the combs—and it is provided with an upturned supporting arm 22 at whose upper extremity a stud 23 is attached, the latter serving to support the 30 double flanged pulley 24 whose axis is disposed in the direction of the length of the frame of the slasher—that is, in the direction of the length of the shaft 8. The pulley 24 is disposed between the U-shaped member 20 and the arm 23 and carries on 35 that side facing the U-shaped member an eccentrically disposed boss or projection 25 which is provided with a wrist pin 26 with which one end of a link 27 pivotally connects.

40 The pulley 24 is rotated through the medium on the shaft 8 and to that end the latter shaft carries a double flange pulley 28 over which a belt 29 is turned, the latter being turned also over the pulley 24. Obviously when the shaft 8 turns rotary motion will be imparted to the pulley 24 with the result that the link 27 will be reciprocated and this link is designed to reciprocate 45 the bar 19 at certain specified intervals of time during the passage of the warp threads from the comb to the roller 3^a. To this end there is mounted on the arm 19 a bracket member 30 which is formed with an upturned ear 31 to which the remaining end

of the link 27 is pivotally connected. This bracket 30 is formed with an extension 32 extending in the direction of the length of the arm 19 and toward the pulley 24, the bracket being provided with pairs of spaced 70 lugs 33 and 34 which straddle the arm 19 on the upper edge. The bracket 30 is mounted so as to slide along the arm 19 as the pulley 24 turns, the lugs 33 and 34 obviously securing the bracket from lateral displacement on 75 the upper edge of the arm but at certain times a locking engagement is effected between the bracket and the arm whereby the movement of the bracket is transmitted to the arm. The arm is held normally in a 80 position where the roller 16 will be held out of contact with the side or selvage threads on the warp and to this end there is provided a spring 35 having one end connected to a laterally extending bracket 36 85 formed with the U-shaped member 20. The other end of this spring connects at an intermediate point with a small rod member 37 which is made preferably of a single piece of wire and formed with an eye 38 90 with which the end of the spring 35 connects. One extremity of this rod member 37 is pivotally connected to the arm 19 at 39 but the other extremity of this rod member is free. Obviously the spring will serve to 95 draw the arm 19 inward until the lug 40 on the latter contacts with one leg of the U-shaped member 20 and the arm will be moved against the tension of the spring to 100 the roller 16 inward where it will contact with the selvage thread of the warp.

Pivottally mounted on the arm 19 on one side thereof there is a pawl 41 the tail of which is engaged by the free end of the rod 105 member 37 to keep the nose of the pawl depressed, the tail and nose of the pawl being on opposite sides of the pivot connection. The pawl is designed to be engaged on the nose by a lip 42 formed on the extension 110 32 of the bracket 30 but this lip may only engage the pawl when the nose of the latter is raised and means hereinafter described is provided for raising the nose. The lip 32, however, is always operatively connected 115 with the periphery of the toothed disk 43, the latter being rotatably mounted on a stud 44 carried by an upstanding support 45 formed with the U-shaped member 20. This disk is provided on its one side with a plurality of axially disposed pins 46 designed to operatively engage a lever 47 carried by a register or counter 48 which is supported on a bracket portion 49 also formed with the U-shaped member 20.

120 When the pawl 41 has its nose out of engagement with the lip 42 of the extension 32 of the bracket 30, the bracket will only slide backward and forward along the arm 19 as the pulley 24 turns, the spring 35 ob- 125 130

viously serving to keep the arm 19 in a position where its lug 40 contacts with one leg of the U-shaped member. By the provision of the free extending end of the rod 57, the spring also serves to keep the pawl 41 positioned where its nose may not be engaged by the lip 42. Thus the pulley 24 may turn and the bracket 30 be moved as before described, the register the while operating because of the turning movement imparted to the toothed disk 43 as the bracket 30 moves.

After a specified length of warp has passed the roller 16, however, the arm 19 is designed to be forced in toward the warp until the roller contacts with the outermost warp threads and forces them in toward adjacent threads to provide the gap 15 previously referred to. To this end there is mounted on the shaft 13 a cam 50, the periphery of which follows the outline of a spiral, thus providing a direct drop from the highest point to the lowest point of the cam, as indicated at 51 in Fig. 5. Playing on the periphery of this cam 50 there is the extremity of one arm of a bell crank lever 52. This lever is pivotally mounted, as at 53, on a bracket 54 formed with one of the bearing supports 14. The extremity of the remaining arm of this lever pivotally connects with one end of a bar 55, the other extremity of this bar passing slidably through a slot formed transversely through the arm 19. That end of the bar 55 passing through the arm 19 is tapered off as indicated at 56 and this tapered end or nose of the bar passes under the nose end of the pawl 41. Obviously as the shaft 13 turns the cam 50 is turned with it and the bell crank lever 52 is rocked on its pivot 53 against the pressure of a spring 57 which is attached on the bracket 54 and bears against that arm of the lever 52 to which the bar 55 is connected. The spring serves to keep the bell crank lever in contact with the periphery of the cam and thus provides for the rocking of the lever during the movement of the cam, this rocking of the lever, of course, imparting a reciprocating movement to the bar 55 causing the latter to move in and out through the slot formed in the arm 19. When the bell crank lever is on the highest point of the cam, the bar 55 reaches the limit of its movement through the arm 19 in the direction of the disk 43. In such a position of the bar the under edge of the pawl 41 adjacent the nose is engaged by the tapered end of the bar and raised so that the nose reaches a point where it may be engaged by the lip 42 of the extension of the bracket 30. When the bracket moves forward due to the turning of the pulley 24, it serves, by engagement of the lip 42 with the pawl 41, to carry the arm 19 forward with it against the tension of the

spring 35. The roller 16, therefore, is brought into contact with the outer threads of the warp and the latter are forced in against the adjacent threads, the sizing on adjacent threads causing them to adhere together and produce the gaps 15. When the arm of the bell crank lever drops to the lowest point on the cam 50 as indicated at 51, the bar 55 is withdrawn from its former position and the pawl 41 is permitted to assume its normal position, the spring 35 at this time drawing the arm 19 backward and raising the tail and depressing the nose of the pawl. The arm 19 thus remains inert until the cam 50 again effects the operation of the bar 55. Obviously the angular velocity of the shaft 13 is low and its speed ratio with reference to the speed of the shafts on other parts of the slasher is such that the bar 55 is operated at the proper intervals to raise the roller 16 to produce the gaps 15 at the desired points on the warp.

After the warp has been prepared in the slasher and finisher, as before described, and has been wound upon the beam 5, the beam is transferred to the loom, as is the usual practice, and the gaps formed in the selvage edge of the warp permit the actuation of a member traversing the selvage edge, this member dropping each time a gap is encountered and, being operatively connected to the loom stopping mechanism, serves to bring the loom to a stop. Such a member and its means for operating the loom stop are shown in the applicant's co-pending application, filed May 13, 1920 and bearing Serial Number 381,072.

The invention having been described, what is claimed as new and useful is:

1. The combination with a slasher, of a member for engaging the outermost warp threads of a warp carried on the slasher, and operative connections between said member and the slasher whereby the member is brought into contact with the said threads at predetermined intervals and offsets them.

2. The combination with a slasher, of a rotatably mounted grooved roller, an arm at the end of which the roller is carried, and means for moving the arm inward at predetermined intervals for the useful purpose specified.

3. The combination with a slasher, of a member carried thereby for engaging the selvage warp threads on the slasher so as to create gaps therein at specified points, and operative connections between said member and the slasher.

4. The combination with a slasher, of an arm mounted on the frame thereof and movable in toward the selvage warp threads, and means operatively connecting said arm to the slasher mechanism so that the said movement may be effected at specified intervals.

- tervals during the operation of the slasher to offset the said selvage threads.
5. The combination with a slasher, of a member engageable with the selvage warp threads carried thereby, and operative connections between said member and the slasher mechanism to effect the engagement of said member with said threads so as to provide gaps in the warp at the selvage edge.
10. 6. The combination with a slasher, of a transversely disposed slidably mounted arm carried on the frame thereof, a grooved roller carried at one extremity of the arm, resilient means tending to draw the arm backward, and means for moving the arm forward at specified intervals to bring said grooved roller into contact with the selvage warp threads carried by the slasher to effect a gap in the warp selvage for the useful purpose specified.
15. 7. The combination with a slasher, of a slidably mounted transversely disposed arm carried on the frame of the slasher, a grooved roller carried at one extremity of the arm, a bracket slidably mounted on the arm, resilient means holding the arm normally inert, means for moving the bracket backward and forward, and means for automatically and positively engaging the bracket with the arm to render the latter active for the useful purpose specified.
20. 8. The combination with a slasher, of a slidably mounted transversely disposed arm carried on the frame of the slasher, a grooved roller carried at one extremity of the arm, a bracket slidably mounted on the arm, resilient means holding the arm normally inert, a rotatably mounted pulley, a connecting rod between said pulley and said bracket whereby the latter may be reciprocated, and automatic means for positively connecting the bracket with the arm to effect the movement of the latter to bring the grooved roller into engagement with and offset the selvage warp threads carried on the slasher.
25. 9. The combination with a slasher, of a transversely disposed slidably mounted arm carried on the slasher, means carried at one end of the arm for engagement with the selvage warp threads carried on the slasher, a rotatably mounted pulley, a bracket carried by and slidably with respect to the arm, and automatic means positively connecting the bracket with the arm at specified periods during rotation of the said pulley, whereby the warp thread engaging means is brought into contact with the selvage warp threads for the useful purpose specified.
30. 10. The combination with a slasher, of a U-shaped member carried on the slasher frame, an arm slidably mounted in said U-shaped member, a grooved roller carried at one end of the arm, a rotatably mounted pulley, a bracket slidably mounted on the arm, a pawl carried by the arm, connections between the pulley and the bracket whereby the latter is reciprocated, and means for periodically engaging the pawl with the bracket to effect movement of the arm at certain intervals for the useful purpose specified.
35. 11. The combination with a slasher, of a U-shaped member carried on the slasher frame, an arm slidably mounted in said U-shaped member, a grooved roller carried at one end of the arm, a rotatably mounted pulley, a bracket slidably mounted on the arm, a pawl carried by the arm, connections between the pulley and the bracket whereby the latter is reciprocated, and automatic means for periodically engaging the pawl with the bracket to effect movement of the arm at certain intervals for the useful purpose specified.
40. 12. The combination with a slasher, of a U-shaped member mounted on the slasher frame, an arm slidably mounted in the legs of said U-shaped member, a spring tensioned between the arm and the U-shaped member to hold the arm normally inert, a bracket slidably mounted on the arm, means for reciprocating the bracket independent of the arm, means for positively connecting the bracket to the arm, and means for operating the last said means at specified intervals so that the arm may be moved inward to engage and offset the selvage warp threads.
45. 13. The combination with a slasher, of an arm, means for slidably supporting the arm on the slasher frame, selvage warp thread engaging means carried at one end of the arm, a bracket slidably mounted on the arm, means for reciprocating the bracket independent of the arm, a pawl pivotally mounted on the arm and engageable with the bracket, a spring having one end connected with the arm supporting means, means for attachment to the other end of the spring whereby the tension of the latter may be exerted on the arm to hold it normally inert and exerted on the pawl to hold it out of engagement with the bracket, and means for positively engaging the pawl with the bracket for the useful purpose specified.
50. 14. The combination with a slasher, of an arm, means for slidably supporting the arm on the slasher frame, selvage warp thread engaging means carried at one end of the arm, a bracket slidably mounted on the arm, means for reciprocating the bracket independent of the arm, a pawl pivotally mounted on the arm and engageable with the bracket, a spring having one end connected with the arm supporting means, means for attachment to the other end of the spring whereby the tension of the latter may be exerted on the arm to hold it normally inert and exerted on the pawl to hold it out of engagement with the bracket, and automatic means for positively engaging the pawl with the bracket for the useful purpose specified.

the bracket at predetermined periods of time for the useful purpose specified.

15. The combination with a slasher, of an arm, means for slidably supporting the arm on the slasher frame, selvage warp thread engaging means carried at one end of the arm, a bracket slidably mounted on the arm, means for reciprocating the bracket independent of the arm, a pawl pivotally mounted on the arm and engageable with the bracket, a spring having one end connected with the arm supporting means, means for attachment to the other end of the spring whereby the tension of the latter may be exerted on the arm to hold it normally inert and exerted on the pawl to hold it out of

engagement with the bracket, a bar passing slidably through said arm and engageable with said pawl to operatively engage the pawl with the bracket, and means for reciprocating said bar to effect the engagement of the pawl with the bracket at predetermined intervals so that the arm may be moved inward to engage and offset the selvage warp threads. 20

16. The combination with a slasher, of means having operative connection with the slasher to produce gaps in the selvage edge of a warp carried on the slasher. 25

In testimony whereof he affixes his signature. 30

GEORGE H. WILSON.
